UNITED STATES PATENT OFFICE.

LEWIS H. THOMAS, OF THOMASVILLE, ILLINOIS.

NOSE DEVICE FOR HOGS.

No. 832,349.

Specification of Letters Patent.

Patented Oct. 2, 1906.

Application filed April 25, 1906. Serial No. 313,692.

To all whom it may concern:

Be it known that I, LEWIS H. THOMAS, a citizen of the United States, residing at Thomasville, in the county of Montgomery and State of Illinois, have invented a new and useful Improvement in Nose Devices for Hogs, of which the following is a specification, reference being had to the accompanying drawings.

10 My improvement relates particularly to devices to be secured to the noses of young hogs for the purpose of preventing them from rooting.

The object of the invention is to provide 15 such a device which shall be simple in form and efficient in action.

In the accompanying drawings, Figure 1 is a front elevation. Fig. 2 is a side elevation.

Referring to said drawings, 1 is a roller 20 mounted rotatably upon a wire stirrup 2. Said stirrup is preferably formed of wire. The free end of each shank 3 of the stirrup is provided with an eye 4. Said stirrup, carrying the roller as described, is supported by 25 a ring 5, which extends through the eyes 4 of

the stirrup. Said ring is open opposite said eyes, and the device is applied to the nose of the pig by pressing the ends of the metal constituting the ring horizontally through the cartilage which is located between the nostrils. When the pig tries to root, the roller 1 impinges upon the ground and is rotated.

I claim as my invention—

1. In a device of the nature described, the combination with an open ring, of a stirrup 35 supported by said ring, and a roller supported by said stirrup, substantially as described.

2. In a device of the nature described, an open wire ring, a stirrup having eyes through which said ring extends, and a roller supported by said stirrup, substantially as described.

In testimony whereof I have signed my name, in presence of two witnesses, this 19th day of April, 1906.

LEWIS H. THOMAS.
